JOHN T. MORRIS, OF WYNNE, MARYLAND, ASSIGNOR TO LYDIA A. MORRIS, OF ST. INIGOES, MARYLAND.

VALVE.

1,257,011.

Specification of Letters Patent. Patented Feb. 19, 1918.

Application filed February 15, 1916. Serial No. 78,449.

To all whom it may concern:

Be it known that I, JOHN T. MORRIS, a citizen of the United States of America, and a resident of Wynne, Maryland, have 5 invented certain new and useful Improvements in Valves, of which the following is a specification.

This invention relates to a novel construction of valves whereby the ready removal 10 of a defective valve may be effected, and whereby a new valve may be inserted and locked in place with equal facility, and this I accomplish by such a construction of the valve-supporting parts, and of the valve 15 seat and valve flap that the two latter may be removed and inserted through the former, and may be readily locked in place without necessitating the use of special tools.

20 While the invention is applicable generally to valves, it finds a special field of utility in connection with the foot valves present in pumps, or in the foot pipes thereof, and especially in connection with the 25 foot valves of what are known as bilge pumps, these latter consisting of sheet metal cylinders of a number of feet in length in which reciprocate valved pistons, and which terminate at their bases in foot castings, supporting check or intake valves. It is the practice to solder the foot castings 30 in the sheet metal cylinders of these pumps, and to replace a defective valve flap has necessitated the unsoldering of the foot 35 casting; the replacement of the defective flap valve with a new one, and a re-soldering of the foot casting to the cylinder. My invention is therefore shown in connection with a foot casting of such a bilge pump, 40 although it is obvious that it is not restricted thereto.

The invention consists in the construction, arrangement, and combination of the several parts of which it is composed, as will 45 be hereinafter more fully described and claimed.

Referring to the accompanying drawings in which corresponding parts are designated by corresponding marks of refer- 50 ence,

Figure 1 is a vertical section through the base of a bilge pump having my invention applied thereto.

Fig. 2 is a perspective view of a valve flap

capable of use in my invention. It is shown 55 merely for the purposes of illustration.

Fig. 3 is an inverted perspective view of a removable valve seat embodying this invention, and adapted to be used in the structure shown in Fig. 1.

Fig. 4 is a perspective view of a valve-supporting member in the form of a foot casting, embodying this invention and adapted to be used in the structure shown 60 in Fig. 1.

Fig. 5 is a perspective view showing the manner of removing or assembling a valve flap and valve seat through the foot casting.

Fig. 6 is a plan view showing a transitory position assumed by the parts after the 70 insertion of a valve flap and seat in the foot-casting, and before the same are locked therein.

Fig. 7 is a similar view, but showing the locked position of the parts. This figure is 75 a horizontal section taken on lines X'—X' of Fig. 1.

Referring to Fig. 1, 1 represents the sheet metal cylinder of a bilge pump, and in its lower end is properly secured, as by soldering, a foot-casting 2 which may be provided with feet 3. Intermediate of its height, the foot casting is provided with an internal flange 4, which provides a support for the valve parts, and the inner wall 80 of the casting has above such flange a plurality of ears 5. In the drawings, four such ears are shown equally spaced apart around the casting, and designated respectively as 5, 5^a, 5^b and 5^c. The inside of this flange 90 has a minor and major diameter preferably effected by forming slots 6 therein. These slots preferably do not extend throughout the full width of the flange, and therefore leave between their bases and the inner 95 wall of the casting a portion of the flange, so that the flange may be said to be continuous adjacent to such a wall. By preference, the location of the slots is directly below the ears 5^a and 5^c.

The movable element 6 of the valve may be of any approved construction. As shown, it consists of a flexible disk.

The valve seat 7 is in the form of a washer having major and minor external diameters. As shown this is effected by forming opposite sides of the washer by parallel chords 7^a, and the diameter of the washer 105

from chord to chord should be less than the major diameter of the flange 4, in the foot casting, to permit the washer to be inserted therethrough when such minor diameter of the washer coincides with the major diameter of the flange. It should also be less than the distance separating the inner faces of the ears 5^a and 5^b. In addition to having its periphery interrupted by the chord 7^a, the washer has a recess 7^b formed in its front edge. By preference, the metal of the washer around the central aperture is struck down into a tongue 7^c, and a projecting ear 7^d. The major diameter of the washer should not be greater than the inner diameter of the cylindrical wall of the foot-casting, to permit such washer to be inserted therein.

The valve element 6 may be secured at 20 one part to the washer by a rivet, bolt or screw 8. By preference, the lower end of this screw is located within the opening in the shoulder 4.

The washer and valve-element will be assembled together when removed from the pump. The valve element should not project past the straight edges of the washer element formed by the chord 7^a.

When the washer and valve element are 30 in place upon the supporting member formed by the flange 4, they will have the angular relation thereon shown in Fig. 7, that is to say, the edges of the washer will be under the ears 5, 5^a, 5^b and 5^c on the foot-casting which will hold the valve seat on the flange of such casting. If it be desired to remove a defective valve, the washer and valve will be rotated in the direction of the arrow in Fig. 7, to the position shown in Fig. 6, in which position the notch 7^b in the washer is beneath the ear 5^b on the foot casting, and in which the washer is freed from the ears 5^a and 5^c, by reason of its minor axis becoming sufficiently non-coincident with the line joining the ears 5^a and 5^c. The forward edge of the washer may be now lifted as illustrated in dotted lines in Fig. 1, withdrawing the rear edge of the washer from beneath the ear 5, permitting the whole washer to tilt and be given a practically vertical position within the barrel of the pump, after which the valve may be passed downwardly through the slots 6, as illustrated in Fig. 5, in which position the minor external diameter of the washer element is coincident with the major internal diameter of the valve supporting part. These movements are facilitated by using the projection 7^d on the washer as a handle. To insert a new valve, a washer and valve element are inserted upwardly through the slots 6 as illustrated in Fig. 5, until above the valve-supporting flange 4. The valve washer is then tilted and

lowered on the flange 4, with its rear edge 65 beneath the ear 5, and then allowed to rest on such flange in the position shown in Fig. 6. By now rotating the valve washer on its supporting seat in the direction of the arrow, Fig. 6, the ears 5^a, 5^b and 5^c are brought 70 over the edges of the washer, and lock the same upon the seat. By preference, the lower edges of the ears 5^a, 5^b and 5^c are slightly beveled or cammed, so that upon the movement of the washer in the direction of the arrow in Fig. 6, the edge of the washer as it passes beneath them, will be forced down upon the flange, and that the friction resulting therefrom will prevent the accidental unlocking movement of 75 the washer. If desired to insure against this movement of the washer, a notch 9 may be formed in the inner edge of the seat, and into this notch the tongue 7^c upon the washer, may be forced after the proper 85 rotation has been given to the seat. This angular shifting of the valve-seat on the supporting element brings their minor and major axes, respectively, out of coincidence, 90 and causes the edge of the valve-seat to rest above the continuous portion of the flange 4, against which it will be held down by the ears 5^a and 5^c, thus preventing leakage at such points.

It will be thus seen that I have provided 95 a construction in which the valve seat and the moving element co-operating therewith, may be removed from, and through the valve-supporting part, without necessitating the uncoupling or disconnection of the 100 latter from the pump cylinder, and by which such valve when repaired, or a new valve, can, in a like manner, be restored to place.

Having thus described my invention what I claim, and desire to secure by Letters Patent is,

1. The combination with a valve-supporting part having minor and major internal diameters, of a removable valve seat resting thereon, and a co-operating moving valve 110 element carried by the valve seat, the valve seat having a minor and a major external diameter, the minor diameter being no greater than the major diameter of the valve-supporting element, and the major 115 diameter of the valve seat being greater than the minor diameter of the valve-supporting element, and means for locking the valve-seat in such angular position on the valve-supporting element that the minor and major diameters of the respective parts are not coincident.

2. The combination with a substantially cylindrical foot-casting having a valve-supporting flange on the interior thereof, such flange having slots in its inner portion whereby the flange is left continuous adjacent to the inner wall of the casting, of a

- valve-seat, and a movable valve element carried thereby, the valve-seat having a major and a minor external diameter, the valve-seat being adapted to pass through the foot-casting when the minor diameter of such seat is coincident with the line joining the slots in the casting, and being capable of being angularly shifted upon such flange when inserted therethrough and rested thereon, and means for holding the washer upon such flange, and against rotation thereon.
3. The combination with a substantially cylindrical foot-casting having an internal flange provided with opposite slots therein, the flange being uninterrupted adjacent to the inner wall of the casting, and the casting having a plurality of locking ears upon its inner wall above such flange, of a valve-seat and movable valve element carried thereby, the valve-seat having a minor external axis less than the distance between the bases of the slots in the flange and having a major axis greater than such distance, and having a recess registering with one of said ears upon the casting when the valve seat is in one angular position upon the flange, and means for shifting the valve-seat from such angular position to another angular position, in which last named angular position the ears over-lie the edges of the washer and the minor axis of the valve seat is not coincident with the line joining the said slots.
5. The combination with a substantially cylindrical foot-casting provided with an internal flange slotted at diametrically opposite points throughout a portion only of its depth, whereby the flange is rendered continuous adjacent to the inner wall of the casting, the casting having a plurality of cam ears thereon, a valve-seat resting on the flange and beneath the cam ears, the valve-seat having a minor external diameter less than the distance between the bases of the slots, and a major external diameter greater than such distance, the minor diameter of the seat not being coincident with the line joining the said slots, the seat having a recess in its periphery adjacent to one of the said ears, but not registering therewith, and a moving valve element supported and carried by the valve seat.
4. The combination with a substantially cylindrical foot-casting having an internal flange provided with opposite slots therein, the flange being uninterrupted adjacent to the inner wall of the casting, and the casting having a plurality of locking ears upon its

inner wall above such flange, the lower faces of such ears forming cams, of a valve seat, and movable valve element carried thereby, the valve-seat having a minor external axis less than the distance between the bases of the slots in the flange, and having a major external axis greater than such distance, and having a recess registering with one of said ears upon the casting when the valve-seat is in one angular position upon the flange, and means for shifting the valve-seat from such angular position to another angular position, in which last named angular position the ears over-lie the edges of the washer and the minor axis of the valve seat is not coincident with the line joining the said slots.

5. The combination with a substantially cylindrical foot-casting provided with an internal flange slotted at diametrically opposite points throughout a portion only of its depth, whereby the flange is rendered continuous adjacent to the inner wall of the casting, the casting having a plurality of cam ears thereon, a valve-seat resting on the flange and beneath the cam ears, the valve-seat having a minor external diameter less than the distance between the bases of the slots, and a major external diameter greater than such distance, the minor diameter of the seat not being coincident with the line joining the said slots, the seat having a recess in its periphery adjacent to one of the said ears, but not registering therewith, and a moving valve element supported and carried by the valve seat.

In testimony whereof I hereunto sign my name this fourth day of February, 1916.

JOHN T. MORRIS.
